SLIDING DOOR

Arthur Thomas Charles Burrows, Hitchin, England, assignor to Geo. W. King Limited, Hitchin, England, a British company

Application June 21, 1950, Serial No. 169,459
In Great Britain June 7, 1949

10 Claims. (Cl. 20—19)

1 This invention relates to sliding doors of the kind which are adapted to be moved back and forth along a horizontal or substantially horizontal path into or away from a closed position.

It is an object of the invention to evolve an arrangement whereby such a door on being moved to a closed position may be caused positively to press or bear against resilient sealing strips or equivalent sealing means disposed around the door opening and thereby to produce an effective seal.

In the specification of my co-pending patent application Serial No. 205,286, filed January 10, 1951, I have described an arrangement for a sliding door of the kind referred to wherein means are associated with the door adapted to impart a vertical movement to the same subsequent to its arrival in the closed position or prior to its movement from such position, such vertical movement being utilised to effect operation of a plurality of latch elements which are located at both the leading and trailing edges of the door and are adapted when the latter is in its closed position to co-operate with fixed brackets or the like disposed at either side of the door opening in such a manner that, depending upon the direction of vertical movement of said door, the latter will be positively urged towards or away from sealing means disposed around said openings.

In the construction above referred to the arrangement is such that the latch elements will always project outwardly beyond the plane of the door face even when they are inoperative, i. e. during traverse movement of the door. Due to the presence of such projections at both the leading and trailing edges of the door, there is always the possibility that damage may be caused either to the latch elements themselves or to adjacent fixtures or fittings or even to personnel during a traverse movement of the door.

It is a further object of the invention to avoid the disadvantages inherent in the prior construction and in accordance therewith the latch elements which are disposed at the leading and trailing edges of the door are so constructed, arranged and adapted to operate as to be retractable behind the plane of the door face during traverse movement of the door in either direction thereby allowing the provision of an entirely flush door face without any projections. The arrangement is such that the latch elements will remain retracted during the entire traverse movement of the door and will be operated to engage the fixed brackets or the like and to ef-

fect sealing of the door after the latter has completed its traverse motion.

In order that the said invention may be clearly understood and readily carried into effect, the same will be hereinafter more fully described with reference to the accompanying drawings in which:

Figure 1 is a front elevational view of a sliding door assembly;

Figure 2 is an end view of the assembly shown in Figure 1 but on a larger scale;

Figure 3 is a front elevational view on an enlarged scale showing a portion of the door assembly and illustrating particularly the mechanism for effecting operation of one set of latch elements;

Figure 4 is an end view of a portion of the mechanism shown in Figure 3;

Figure 5 is a plan view of a portion of the mechanism shown at the right of Figure 3;

Figures 6 and 7 are a front elevational and end view respectively of an alternative mechanism for effecting operation of the latch elements, and

Figure 8 is a part sectional end elevational view of mechanism mounted at the lower part of the door.

Referring to the drawings it will be seen that the door therein illustrated comprises a rigid panel-like structure designated generally by 10, which is capable of being moved back and forth along a predetermined path from an open to a closed position and vice versa. In the embodiment illustrated the door 10 is suspended by means of a rope or cable 11 from two trolleys 12 which are adapted to travel on an overhead track 13, one or both of said trolleys 12 having a drive unit associated therewith in order to provide for traversing movement of the door. Mounted on a third trolley 14 disposed intermediate the trolleys 12 and also running on the track 13 is a hoist unit designated generally by 15, such unit incorporating an electric driving motor, suitable gearing and a winding drum around which passes a hoist chain or cable 17 serving to support a hoist block 18. Freely journalled in the block 18 is a pulley 18' over which the suspension rope or cable 11 is adapted to pass, such rope or cable, as will be apparent from Figure 1, being attached at one end to one of the trolleys 12 and passing thence around freely rotatable sheaves or pulleys 19 to the pulley 18' whence it passes around further sheaves or pulleys 19, the other end being attached to the second trolley 12.

The arrangement so far described is such that when, for example, the door 10 is to be moved

from the closed to the open position the motor of the hoist unit 15 will be operated to effect lifting of said door through a predetermined distance whereafter it will be switched off automatically in any convenient manner and the power operated trolley or trolleys 12 from which said door is suspended will be set in operation to drive the door along the track into its open position. On closing the door a drive is imparted to the power operated trolley or trolleys 12 to move the door into the door opening. When the door reaches the closed position the arrangement is such that the drive to the trolleys 12 will be automatically discontinued while the motor of the hoist unit will be operated automatically to drive the winding drum in such a direction as to result in lowering of the hoist block 18 and hence of the door 10. It is only intended that the door shall be raised or lowered prior to each opening or closing movement by a comparatively small amount, for example, in the region of two inches or thereabouts.

The raising or lowering movement of the door above described is utilised to effect or control the sealing of the latter when in its closed position as will now be more fully described.

Disposed at each lateral edge of the door 10, i. e. the leading and trailing edges, is a series of latch elements 20, the elements at each edge being spaced apart relatively to each other and being interconnected by means of a connecting bar 21 so as to be moved simultaneously. The connecting bar 21 which extends parallel to the edge of the door 10 is pivotally connected to links 22 which are in turn capable of angular movement about fixed pivots 23 carried by the door. The respective link mechanisms on the leading and trailing edges of the door are both fitted in the same plane and are not offset with respect to each other. The arrangement is such that when the door starts its transverse movement from the closed position all of the latch elements 20 at the leading and trailing edges of said door will be retracted behind the plane of the door face due to an angular movement of the links 22 about their fixed pivots. Again, as the door reaches its closed position and comes to a standstill, the latch elements 20 at both the leading and trailing edges will be lowered or projected by virtue of a reverse angular movement of the links 22 until each one of said elements engages with a fixed hook unit or bracket 24 disposed at the appropriate side of the door opening. Preferably an adjustable stop is associated with each connecting bar 21 such stop being adapted before the latch elements 20 make full contact with hook units or brackets 24, to co-operate with one of the links and to prevent further downward movement of the latch elements, thereby to ensure an appropriate working clearance.

The arrangement is such that the projection and retraction of the latch elements 20 will take place during the initial part of the downward movement of the door and during the final part of its upward movement respectively, the final part of the downward movement and the initial part of the upward movement being utilised respectively to effect and to break the sealing of said door. The movement required to retract and project or lower each series of latch elements 20 is derived from the relative movement between the door (when the latter is subjected to the vertical movement above described), and a dog or other attachment 25 fixed to the door suspension rope or cable 11 above referred to.

The dog or other attachment 25 is adapted on upward movement of the door to impart a clockwise angular movement to a pivoted lever 26, the movement of which latter is transmitted by means of a wire rope 27 passing around sheaves 28 and 29 to a master link 30 fitted at the upper part of the door and associated with the connecting bar 21, the arrangement being such that on operation of the lever 26 the master link will be swung upwardly thereby lifting the bar 21 and effecting retraction of the latch elements 20 behind the plane of the door. When the door is lowered to release the pressure of the dog or attachment 25 on the lever 26, the latter is caused to swing in the reverse direction thereby to effect reverse angular movement of the master link 30 and projection or lowering of the latch elements 20. Alternatively, as shown in Figures 6 and 7, the dog or attachment 25 may be adapted to co-operate with a lever or cam 31, the resultant movement of the latter being transmitted by means of a shaft or spindle 32 to impart an angular motion to the master link 30 either directly or through the medium of a series of intermediate levers, such as are indicated at 33 and 34. The arrangement is such that the dog or attachment 25 will only be operative during the highest part of the lifting or lowering motion of the door. During lowering of the door as soon as the adjustable stop above referred to becomes operative to limit the downward or projecting movement of the latch elements 20, the lever 26 or 31 co-operating with the dog or attachment will lose contact with the latter and further lowering and actual sealing of the door will thereafter take place.

At each lateral edge, i. e. the leading and trailing edges, the door is provided at its lower part with a guide roller 35 (Figure 8) adapted during traverse movement of the door to run in a guide channel 36 (Figures 2 and 8) in the floor or other surface. As described in the prior specification above referred to, when the door reaches its closed position and is lowered the latch elements 20 and their connecting bars or rods 21 will, subsequent to projection, have a toggle like action which, owing to the engagement of said latch elements with the fixed hook units or brackets 24, will cause the door to be moved bodily inwardly with respect to the plane of the door opening to effect sealing of said door. Again, on lifting of the door prior to the opening movement thereof, the latch elements 20 will be moved initially and prior to retraction to force the door outwardly away from the sealing devices.

In order to allow for this inward and outward movement of the door it is necessary that the guide rollers 35 above referred to shall also be capable of a retractive and projective movement in order to be disengaged from and to engage the guide channel 36 on sealing of the door and on opening of the latter respectively. In the embodiment illustrated in Figures 2 and 8, each guide roller 35 is rotatably mounted on a bar or the like 37 which is supported for free vertical sliding movement in a slotted tube or the like 38 rigidly mounted at the edge of the door. Disposed parallel to the first slotted tube is a second similar tube 39 also mounted at the door edge, in which a second bar or the like 40 is adapted to slide, said second bar having a freely rotatable ball 41 suitably mounted at the lower end thereof. Both of the bars 37 and 40 are linked together by means of a slotted link 42

5

which co-operates respectively with pins 43, 44 carried by said bars and has an arm or extension 45 disposed at a convenient angle to the slotted portion but lying in the same plane, the outer end of such arm or extension 45 being pivotally connected to the lower part of the connecting bar associated with the latch elements.

The arrangement described in the preceding paragraph is adapted to operate as follows: During the traverse movement of the door the latch elements 20 are retracted and the guide rollers 35 at each of the leading and trailing edges of the door are in their lowermost positions and in engagement with the guide channel 36. When the door reaches its closed position and is lowered with the resultant projection or lowering of the latch elements 20 into engagement with the fixed hook units 24 the slotted link 42 connecting the two slideable bars 37 and 40 will have an angular motion imparted thereto due to the connection of the arm or extension 45 with the connecting bar 21 associated with said latch elements. The angular movement of the link 42 is adapted to cause the first bar carrying the guide roller 35 to be lifted vertically to raise said roller clear of the guide channel 36. This action takes place, as will be appreciated, during initial lowering of the door. During further lowering and sealing of the door the ball 41 associated with the second slideable bar 40 will bear on the floor thereby keeping constant the distance between the floor and the point of connection of the arm or extension 45 with the connecting bar 21. As the position of the link 42 will be maintained fixed with relation to the connecting bar 21 associated with the latch elements 20 the guide roller 35 will be held in the same height position clear of the floor while the door is finally lowered for sealing and the inward movement thereof takes place. The arrangement is such that when the guide roller 35 is raised the link 42 will be in such a position, as shown in chain dotted lines in Figure 8, that the slots therein will be horizontal and will thereby allow the requisite inward movement of the door.

On opening of the door it will be appreciated that during the initial raising movement the latch elements 20 will be operative to free the door outwardly away from the sealing devices and during that movement the slotted link 42 at each edge of the door will be retained in the position which it occupied during the final stages of the sealing movement, thereby maintaining the associated guide roller 35 clear of the floor. During the final stage of the lifting movement of the door with consequent retractive movement of the latch elements 20 and raising of the connecting bar 21 at each edge of said door, the slotted link 42 will be caused to move thereby to project the guide roller 35 downwardly and into engagement with the guide channel 36. With the guide roller 35 in the channel 36 the door may then be driven into the open position on operation of the trolleys associated with the carriage.

Instead of employing a hoist unit for effecting the necessary raising and lowering of the door it may be desirable to provide a lifting unit comprising an electric motor which is coupled, through the medium of a fluid coupling and suitable gearing, to a threaded rod rotatably journaled within the door structure in such a manner that its longitudinal axis is vertical or substantially so. Mounted on the threaded rod or the like is a correspondingly threaded member

6

in the form of a nut or equivalent device which is normally restrained against rotation and is further adapted, on rotation of said rod or the like, to be moved vertically upwardly or downwardly relatively to the latter. Attached to the threaded member, which may be constrained to move in suitable guides, is a pair of ropes or cables each of which is adapted to pass from said member and around a suitable sheave or pulley, its free end being anchored to one of the trolleys on which the door is suspended. The sheaves or pulleys are preferably spaced equidistantly from the vertical centre line of the door at opposite sides of the latter, the arrangement being such that when the threaded member is moved upwardly due to rotation of the threaded rod in the appropriate direction the door will be lifted while, when said member is moved downwardly a corresponding downward movement of the door will result.

In certain cases, as in the case of doors of considerable weight, it may be desirable to replace the raising and lowering mechanism hereinbefore described by a hoist mechanism capable of imparting a direct lift to the door. For example, a standard or known type of hoist unit may be disposed centrally or substantially centrally with respect to the door such unit being carried by a suitable carrier having wheels or rollers adapted to engage and to run on the fixed overhead track on which the two trolleys which provide for traverse motion to the door are also adapted to run, the arrangement being such that the carrier will be disposed between said two trolleys. The hoist unit so provided includes a hoist block suspended therefrom through the medium of a chain, wire, rope or the like which is associated with a winding drum and passes around suitably disposed sheaves or pulleys, the block being adapted to be raised and lowered in known manner according to the drive imparted to the winding drum. Freely journaled in the hoist block is a sheave or pulley over which one or more suspension ropes or cables, serving to support the door, is or are adapted to pass. Each suspension rope or cable is conveniently anchored at one end to one of the trolleys running on the fixed overhead track and passes thence around suitably disposed sheaves or pulleys carried by the door and around the hoist block sheave or pulley whence it passes around further sheaves or pulleys carried by the door, the other end being anchored to the second trolley on the fixed overhead track. It will be appreciated that suitable means will be provided for controlling the operation of the hoist motor so that raising or lowering of the door will be effected at the appropriate times. As in the embodiment previously described, the abutments for effecting operation of the latch elements on closure of the door will be mounted on or associated with the suspension rope or ropes at a convenient point.

I claim:

1. A sliding door assembly comprising a rigid door slideable back and forth along a predetermined substantially horizontal path into and out of a position wherein it is adapted to close a door opening; sealing mechanism for displacing said door transversely of said path into and out of sealing engagement with the door opening and including brackets fixedly mounted at either side of the door opening, and latch elements pivotally mounted at the leading and trailing edges of the door and movable between inoperative positions wherein they are retracted

behind the plane of the door face and operative positions wherein they project beyond said door face and engage the brackets; means for lifting and lowering said door through a predetermined vertical distance; and means actuated by said lifting and lowering means and operating in response to the vertical movement applied to the door to effect retraction and projection of said latch elements from and into their operative positions.

2. A sliding door assembly comprising a rigid door slidable back and forth along a predetermined substantially horizontal path into and out of a position wherein it is adapted to close a door opening; sealing mechanism for displacing said door transversely of said path into and out of sealing engagement with the door opening and including brackets fixedly mounted at either side of the door opening, a series of link elements pivotally mounted at each of the leading and trailing edges of the door, a bar supported by each series of link elements to lie in a plane parallel to the door edge to which said elements are pivotally attached and movable in said plane both vertically and transversely with respect to said path, and latch means connected to each of said bars and movable with the latter between inoperative positions retracted behind the plane of the door face and operative positions wherein they project beyond said door face to engage said brackets; means for lifting and lowering the door through a predetermined vertical distance; and means actuated by said lifting and lowering means and operating in response to the vertical movement applied to the door to impart movement to said bars thereby to effect retraction and projection of the latch means from and into said operative positions wherein they will engage the brackets thereby to secure the door in its closed position.

3. A sliding door assembly comprising a rigid one piece door slidable back and forth along a predetermined substantially horizontal path into and out of a position wherein it is adapted to close a door opening; sealing mechanism for displacing said door transversely of said path into and out of sealing engagement with the door opening and including brackets fixedly mounted at opposite sides of the door opening, a series of link elements pivotally mounted at each of the leading and trailing edges of the door, a bar supported by each series of link elements to lie in a plane parallel to the door edge to which said elements are pivotally attached and movable in said plane both vertically and transversely with respect to said path, and a plurality of latch elements formed integrally with said bar and movable with the latter between inoperative positions retracted behind the plane of the door face and operative positions wherein they project beyond said door face to engage said brackets; means for lifting and lowering the door through a predetermined vertical distance; and means actuated by said lifting and lowering means and operating in response to the vertical movement applied to the door to impart movement to said bars to effect retraction and projection thereof and of the latch elements into and from said inoperative positions wherein they are disposed behind the plane of the door face and from and into said operative positions wherein they will engage the brackets thereby to secure the door in its closed position.

4. A sliding door assembly including a rigid door suspended from an overhead track so as

to be slidable back and forth along a predetermined path into and out of a position wherein it is adapted to close a door opening such assembly comprising brackets fixedly mounted at opposite sides of the door opening, a series of latch elements mounted at each of the leading and trailing edges of the door in such a manner as to be capable of retraction into an operative position wherein they will lie behind the plane of the door and of projection into operative positions wherein they will engage the brackets, a hoist mechanism supported on said overhead track, at least one rope or cable operatively associated with said hoist mechanism and coupled to the door thereby to impart a lifting or lowering motion to the latter on operation of said hoist mechanism, an attachment associated with said rope or cable, and a pivoted member disposed in the path of said attachment and operatively coupled to said latch elements, the arrangement being such that on raising or lowering of the door the attachment will be caused to cooperate with the pivoted member thereby to cause retraction or projection of said latch elements from or into their operative positions.

5. A sliding door assembly including a rigid door suspended from an overhead track so as to be slidable back and forth along a predetermined path into and out of a position wherein it is adapted to close a door opening such assembly comprising brackets fixedly mounted at opposite sides of the door opening, a series of link elements pivotally mounted at each of the leading and trailing edges of the door, a bar supported by each series of link elements to lie in a plane parallel to the door edge to which said elements are pivotally attached, latch means associated with each of said bars, a hoist mechanism supported on said overhead track, at least one rope or cable operatively associated with said hoist mechanism and coupled to the door thereby to impart a lifting or lowering motion to the latter on operation of said hoist mechanism, an abutment member associated with said rope or cable, a double armed lever mounted on said door, one arm of which is adapted to cooperate with said abutment member, and means operatively connecting the second arm of said lever to one of the links associated with each of the bars, the arrangement being such that on raising or lowering of the door the abutment member will be caused to cooperate with the double armed lever thereby to cause retraction or projection of said latch elements from or into operative positions wherein they will engage the brackets to secure the door in its closed position.

6. A sliding door assembly including a rigid door suspended from an overhead track so as to be slidable back and forth along a predetermined path into and out of a position wherein it is adapted to close a door opening, such assembly comprising brackets fixedly mounted at opposite sides of the door opening, a series of link elements pivotally mounted at each of the leading and trailing edges of the door, a bar supported by each series of link elements to lie in a plane parallel to the door edge to which said elements are attached, latch means associated with each of said bars, a hoist mechanism supported on said overhead track, at least one rope or cable operatively associated with said hoist mechanism and coupled to the door thereby to impart a lifting or lowering motion to the

latter on operation of said hoist mechanism, an abutment member associated with said rope or cable, a shaft rotatably journaled on said door, an arm fixedly mounted on said shaft to cooperate with said abutment member and a linkage mechanism serving to couple said shaft to one of the link elements associated with each of said bars, the arrangement being such that on lifting or lowering of the door the abutment member will be caused to cooperate with the arm thereby to cause movement of the bars and retraction or projection of said latch elements from or into operative positions wherein they will engage the brackets to secure the door in its closed position.

7. A sliding door assembly comprising a rigid door suspended from an overhead track so as to be slideable back and forth along a predetermined substantially horizontal path into and out of a position wherein it is adapted to close a door opening, guide rollers disposed at the lower part of said door for engagement during sliding movement thereof with a fixed track extending along said path below the lower edge of the door, brackets fixedly mounted at either side of the door opening, latch elements pivotally mounted at the leading and trailing edges of the door for movement between retracted inoperative positions wherein they lie behind the plane of the door face and projecting operative positions wherein they engage the brackets, means movably supporting said guide rollers at the lower edge of said door for projection and retraction, respectively, into and from operative positions wherein said rollers engage the track below the door, means for lifting and lowering the door through a predetermined vertical distance and means actuated by said lifting and lowering means and operating in response to the vertical movement applied to the door to effect retraction and projection of said latch elements from and into their operative positions and simultaneous projection and retraction of the guide rollers into and from their operative positions.

8. A sliding door assembly comprising a rigid door suspended from an overhead track so as to be slideable back and forth along a predetermined substantially horizontal path into and out of a position wherein it is adapted to close a door opening, said door having at its lower part guide rollers adapted during sliding movement thereof to engage a fixed track extending along said path below the lower edge of the door, brackets fixedly mounted at opposite sides of the door opening, a series of link elements pivotally mounted at each of the leading and trailing edges of the door, a bar supported by each series of link elements to lie in a plane parallel to the door edge to which said elements are

attached and movable in said plane both vertically and transversely with respect to said path, latch means connected to each of said bars and movable with the latter between inoperative positions retracted behind the plane of the door face and operative positions wherein they project beyond said door face to engage said brackets, stationary vertically extending guide means at the lower part of the door and adjacent each of the leading and trailing edges thereof, a member mounted for vertical sliding movement in each of said guide means and carrying one of said guide rollers, a linkage mechanism coupling each of said roller carrying members to the bar at the related edge of the door, means for lifting and lowering the door through a predetermined vertical distance, and means actuated by said lifting and lowering means and operative in response to the vertical movement applied to the door to impart movement to said bars and thereby to effect retraction and projection of the latch means from and into said operative positions wherein they will engage the brackets thereby to secure the door in its closed position and simultaneous projection and retraction of the guide rollers into and from said operative positions wherein they will engage the track below the lower edge of the door.

9. A sliding door as in claim 8, in which a second member capable of vertical sliding movement is disposed in parallel relationship with respect to each of the first mentioned members carrying the guide rollers, link means coupling said first and second members and having an extension which is in turn pivotally connected to the related bar, and said second member being adapted on projection of the latch means to bear on the floor or other surface thereby to provide a fulcrum for the link which will allow the latter to effect raising of said first member.

10. A sliding door as in claim 9, in which said link is coupled to said first and second members by pin and slot connections, the arrangement being such that, on retraction of said first member to bring the guide roller out of engagement with the track, movement of the door laterally with respect to said track will be allowed.

50 ARTHUR THOMAS CHARLES BURROWS.
